John J. Lynch

UNITED STATES PATENT OFFICE

LIVINGSTON FOUNTAIN, OF NEW YORK, N. Y.

LOCK TAB EASEL

Application filed April 30, 1930. Serial No. 448,637.

This invention relates to easel constructions and in particular to an easel arranged in combination with a member to be supported so that the easel lies flat against the member when not in use and is foldable to a position to support the member at any suitable angle.

A particular object of my invention is to provide in a construction of the character referred to, a gluing strip through the medium of which the wing is attached to the member to be supported, the gluing strip being unbroken throughout its entire length whereby the easel may be applied by machinery in order to cut down the cost of production.

A still further object of my invention is to provide a single lock tab which is cut completely out of the wing, the wing cut out and the tab being each provided with notches whereby they may relatively interlock to prevent sidewise movement of the wing after it has been bent to a supporting position.

A still further and equally important object is the provision of a diagonal score on the lock tab which permits the bending of the tab to its locking position and at the same time provides a portion of the lock tab which is arranged to abut the member to be supported so that the wing is solidly held and the member substantially supported.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Figure 1 is a rear view in elevation of a member to be supported to which is secured my improved easel construction.

Figure 2 is a view in side elevation of the easel construction as illustrated in Figure 1, the wing of the easel being moved out to supporting position and being maintained in such position through the medium of the folded lock tab, and

Figure 3 is a view in perspective showing the wing opened up and also showing how a portion of the lock tab is used against the member to be supported to provide a solid construction and give substantial support when the wing is open.

Referring to the drawings in detail, 5 indicates a front plate or member to be supported to which is arranged to be secured as by gluing, the easel denoted generally, by the numeral 6 and comprising the gluing strip 7 scored vertically throughout its length as at 8. This score line 8 defines one edge of a wing 9 whose bottom is cut on the bias as at 10 to permit angular support of the front piece 5 when the same is to be exhibited.

The wing 9 tapers in width from bottom to top and intermediate its ends, it is punched or cut out along the lines 11 and 12 to provide a lock tab 13. This lock tab at its top edge is provided with an inwardly cut tab notch 14 and at the meeting point of the cut lines 11 and 12, there is provided in the wing 9, a notch 15 which when the tab is opened 70 and the wing in supporting position, cooperates with the notch 14 of the tab to lock the wing and tab together.

The tab 13 is provided adjacent its lower portion with a diagonal score line 16 which provides for the folding over of the top portion of the tab to substantially horizontal position so that the wing 9 when swung around will lock in the tab notch 14. This diagonal score line 16 also provides a bottom portion 17 on the tab, which, as illustrated in Figure 3, abuts the rear surface of the member 5 to be supported and forms a brace which effectively keeps the wing open and provides a rigid structure so that a front member of unusual weight or size may be conveniently supported by my easel construction.

Attention is directed to the fact also, that my improved easel construction may be either right or left, that is, in Figures 1 and 2, the easel has been shown with the wing extending to the right, while in Figure 3, the wing would normally extend to the left, when the wing is folded flat against the front member 5.

It will be noted that the easel is adapted for low cost in manufacture since it is formed

from a single piece of stock by simple cutting and folding operations. The several cuts necessary for the formation of the easel as well as the scoring may be readily accomplished in a single operation by a die. The construction of the easel is simple and its operation requires little time or effort in that the wing is swung open and the tab 13 is swung downwardly until the notch 14 therein comes into engagement with and locks in the wing notch 15, the bending of the tab 13 being accomplished along the score line 16.

While I have illustrated and described my invention with some degree of particularity, I realize that in practice various alterations therein may be made without departing from the spirit of the invention or the scope of the appended claims.

What I claim is:—

- 20 1. An easel comprising in combination, a gluing strip arranged to be applied to a member to be supported, a wing secured to the strip and foldable relatively thereto, a tab cut wholly out of said wing and scored to provide a foldable tab portion, and notches in the wing and in the tab arranged to engage each other for securing the tab and wing in open supporting position, when said portion is folded.
- 25 2. An easel comprising in combination, a gluing strip arranged to be applied to a member to be supported, a wing secured to the strip and foldable relatively thereto, a foldable tab cut wholly out of said wing, and notches in the wing and in the tab arranged to engage each other for securing the tab and wing in open supporting position when the tab is folded.
- 30 3. An easel comprising in combination, a gluing strip arranged to be applied to a member to be supported, a wing secured to the strip and foldable relatively thereto, a tab cut in said wing and scored diagonally to provide a foldable tab portion, a notch in the wing, and a notch in the tab for engaging said wing notch when the tab portion is folded.
- 35 4. An easel comprising in combination, a gluing strip arranged to be applied to a member to be supported, a wing secured to the strip and foldable relatively thereto, a tab cut in said wing and scored diagonally to provide a foldable tab portion, a notch in the wing, a notch in the tab for engaging said wing notch when the foldable tab portion is disposed horizontally, and the portion of the tab below said diagonal score being arranged to abut the surface of the member to be supported when said tab portion is folded.
- 40 5. In testimony whereof, I have signed my name to this specification this 21st day of April, 1930.

LIVINGSTON FOUNTAIN. [L.S.]
